ATTORNEY.

UNITED STATES PATENT OFFICE.

HUGH J. McGEE, OF SEATTLE, WASHINGTON.

DESIGN FOR A STREET-LIGHTING DEVICE.

58,790.

Specification for Design.

Patented Aug. 30, 1921.

Application filed January 24, 1921. Serial No. 439,699. Term of patent 3½ years.

To all whom it may concern:

Be it known that I, HUGH J. McGEE, a citizen of the United States, and a resident of Seattle, in the county of King and the State of Washington, have invented a new, original, and ornamental Design for a Street-Lighting Device, of which the following is a specification, reference being had to the accompanying drawings, forming a part thereof.

In the drawings Figure 1 is a side elevation of the device showing my new design, Fig. 2 is a plan view of Fig. 1.

I claim:

The ornamental design for a street lighting device as shown.

HUGH J. McGEE.
